UNITED STATES PATENT OFFICE.

JAMES C. TAYLOR, OF BOSTON, MASSACHUSETTS, ASSIGNOR OF ONE-THIRD TO CHARLES H. MAIERS, OF NORWOOD, MASSACHUSETTS, AND ONE-THIRD TO JOHN GALWAY, OF BOSTON, MASSACHUSETTS.

AUTOMATIC SHUT-OFF VALVE.

1,106,427.

Specification of Letters Patent. Patented Aug. 11, 1914.

Application filed July 17, 1913. Serial No. 779,471.

To all whom it may concern:

Be it known that I, JAMES C. TAYLOR, a citizen of the United States, residing at Boston, county of Suffolk, State of Massachusetts, have invented an Improvement in Automatic Shut-Off Valves, of which the following description, in connection with the accompanying drawing, is a specification, like characters on the drawing representing like parts.

This invention relates to automatic shut-off valves such as are placed between the gas meter and supply pipe to shut off the gas in case of fire, and it provides a fool-proof and malice-proof device of this nature. These devices usually have a valve which is normally held by fusible means in position to allow the free passage of gas, said fusible means being so disposed as to become fused when the temperature adjacent the device increases beyond a certain point, and the valve being so constructed as to find its seat automatically when the fusible means is fused and thereby shut off the flow of gas.

My invention has for an object to provide a device of this class which will be simple in construction and operation and one which it will be impossible either through ignorance or with malicious or fraudulent intent to alter so that it will not operate in case of fire.

Other objects will appear from the following specification in which my device will be fully described and the novel features will be pointed out in the claims hereto appended.

In accordance with my invention I provide a valve casing formed of one integral casting having a fluid passage therethrough and a lateral chamber adjacent to the passage in which a ball-valve is releasably retained by a fusible stop. The device is so arranged that access to the valve is impossible except by removing the stop or entirely disconnecting the device and upon removal of the stop the valve falls shutting off the supply of gas.

Referring to the drawing, Figure 1 is a view showing my improved valve applied between a supply pipe and the gas meter. Fig. 2 is a central longitudinal section of the valve.

Referring to the drawing in detail 1 indicates a gas meter, 2 a gas supply pipe be-

tween which and the gas meter my shut-off 53 is inserted. This shut off comprises a main casting 4 having a passage 5 therethrough which is preferably straight as shown, the lower portion being gradually tapered as at 6 and also having a laterally disposed portion forming a valve-receiving chamber or recess 8 which communicates with the passage 5 above the tapered portion 6 and normally receives a ball-valve 7. Said lateral chamber or recess 8 has an inclined bottom 65 so that the ball valve will roll by gravity therefrom into the tapered portion 6 when it is released, the upper end of said chamber or recess being closed. The ball valve 7 is normally retained in said lateral chamber 8 by a plug 9 of brass or some other heat conducting material which may be screw threaded to fit tightly into a hole 10 in the side of the lateral chamber. To the end of this plug is secured a projection 11 which 75 may be of fusible material or may be of other material and fusibly connected to the plug. The plug 9 is preferably tapered slightly and the aperture 10 will be correspondingly tapered whereby the extent to 80 which the plug can be screwed into the hole will be limited. The plug with its projection 11 is so positioned that it will normally retain the ball valve 7 in its inoperative position in the chamber but if heat is applied 85 to the plug as in the case of a fire occurring the projection 11 will become fused and the ball valve will automatically fall into the tapered portion 6 of the passage as shown in dotted lines at 13 where it will wedge and 90 shut off the supply of gas. If, for any reason the plug 9 is removed by unauthorized persons the ball valve will fall shutting off the gas as in case of fire and it will then be necessary to call a gas fitter before any gas 95 can be used. The plug may be shaped to be operated by a special wrench making it more difficult for unauthorized persons to tamper with the device.

It will be noted that the walls of the 100 chamber 8 form an integral part of the casting 4 and that the only opening through which the ball-valve 7 can be inserted into the chamber 8 is the open end of the casting. Hence after the ball-valve is properly 105 placed in its chamber 8 and the plug 9 is adjusted to hold the ball-valve therein, and the shut-off device is connected with the

supply pipe, there is no way in which the ball-valve can be moved from the casing or tampered with so as to prevent it from working except by disconnecting the shut-off device from the supply pipe. Moreover, if any unauthorized person tampers with the plug 9 and unscrews it any the valve will fall thus shutting off the supply from the meter. It will thus be seen that the shut-off device can not be tampered with so as to render it inoperative without shutting off the gas from the meter and thus giving an indication of the fact that something is wrong.

15 While I have illustrated one embodiment of my invention I do not wish to be limited to the constructional details shown.

Having described my invention, what I claim as new and desire to secure by Letters Patent is:

20 1. A valve comprising a casing having a passage therethrough, a portion of the passage being gradually tapered and a laterally disposed portion integral with said casing forming a valve receiving recess having its outer end closed; said recess opening into the passage above the tapered portion, a ball valve mounted in said recess and adapted to fit the tapered portion and a retaining member having a fusible part positioned to normally hold the ball valve in the lateral chamber.

25 2. An automatic shut-off valve comprising a casing having a straight passage therethrough, a portion thereof being gradually tapered and a laterally disposed portion integral with said casing forming a valve receiving recess having its outer end closed, said recess opening into the passage above

the gradually tapered portion, a ball valve 40 mounted in the lateral chamber and a fusible retaining member holding the ball valve in its position in the lateral chamber adapted upon being heated to allow the ball valve 45 to drop into the tapered portion and wedge therein.

3. A valve comprising a casing having a passage therethrough, and a laterally disposed portion integral with said casing forming a valve receiving recess having its 50 outer end closed, said recess opening into the passage, a ball valve mounted in the lateral recess and adapted to fit the passage, and a retaining member having a fusible part positioned to normally hold the ball valve in 55 the lateral recess.

4. An automatic shut off valve comprising a casing having a passage therethrough, a laterally disposed portion integral with said casing forming a valve receiving recess having its outer end closed, said recess opening into said passage, a ball valve mounted in the lateral recess, and a plug fitting an aperture in the wall of said laterally disposed portion, said plug provided with a fusible 60 portion and so positioned as to normally retain the valve in said lateral recess but adapted upon being heated to allow the valve to drop into said passage, substantially as and for the purpose set forth.

In testimony whereof, I have signed my name to this specification, in the presence of two subscribing witnesses.

JAMES C. TAYLOR.
